United States Patent Office

Des. 178,543
Patented Aug. 14, 1956

178,543

FOOD MIXER

Arthur W. Seyfried and Peter W. Lahr, Racine, Wis., assignors to Scovill Manufacturing Company, Waterbury, Conn., a corporation of Connecticut

Application January 16, 1956, Serial No. 39,780

Term of patent 14 years

(Cl. D44—1)

FIG. 1.

FIG. 2.

FIG. 3.

FIG. 4.

FIG. 5.

Fig. 1 is an elevational side view of a food mixer embodying our new design.

Fig. 2 is an elevational front view of the same.

Fig. 3 is an elevational rear view of the mixer without the beaters.

Fig. 4 is a top plan view of the same.

Fig. 5 is an elevational view showing the bottom of the mixer as it appears when resting on its rearward end.

The dominant features of the design reside in those portions shown in full lines in the drawing.

We claim:

The ornamental design for a food mixer, as shown and described.
